UNITED STATES PATENT OFFICE.

FERDINAND JOHN WICH, OF CAPE TOWN, CAPE COLONY, ASSIGNOR TO LINOTYPE AND MACHINERY LIMITED, OF LONDON, ENGLAND.

ASSEMBLING MECHANISM OF TYPOGRAPHIC COMPOSING-MACHINES EQUIPPED WITH ALTERNATE FONTS.

No. 926,158.

Specification of Letters Patent.

Patented June 29, 1909.

Application filed December 23, 1907. Serial No. 407,687.

To all whom it may concern:

Be it known that I, FERDINAND JOHN WICH, a citizen of the United States of America, residing at the Cumberland Hotel, 5 St. George's street, Cape Town, Cape Colony, have invented new and useful Improvements in the Assembling Mechanism of Typographical Composing-Machines Equipped with Alternative Fonts, of which the following is a specification.

The present invention relates to improvements in the assembling mechanism of typographical composing machines equipped with alternative fonts. A typical machine 15 so equipped is the two-letter variety of the Mergenthaler linotype machine. Each of its matrices is practically a rectangular plate having a recess in each side edge and the formative cavity for the respective type face 20 in and across one of these edges, so that the cavity for the alternative font must be either above or below the one for the normal font. This being the case, the alternating motion necessary to make a matrix present the desired cavity in the composing line, must 25 always be a vertical one—see the specifications of Letters Patent Nos. 449872, 547633 and 615909.

In the accompanying drawings which are 30 to be taken as part of this specification and read therewith:—Figure 1 is a front elevation of as much of the improved assembling mechanism as is necessary to illustrate the present invention; Fig. 2 is a plan of the 35 assembler broken away; Fig. 3 is an elevation as seen from the right-hand side of Fig. 1, and shown partly in vertical section on the line 3—3 of that figure; Fig. 4 is a vertical section also taken on the line 3—3 40 of Fig. 1 but showing the device under a different condition of adjustment, and Fig. 5 is a side elevation showing parts of the mechanism represented in Fig. 3, in a different position from that in which they are 45 shown in that figure.

In the drawings, see Figs. 3 and 4, two matrices 1 are represented in dotted lines, the two formative cavities 2, 3 being for producing printing faces of respectively normal and variant font. When the normal 50 formative cavities 2 are in the composing line, as in Fig. 3, the two bottom lugs 4, 5 of each of the matrices 1 rest upon the ledges 6

and 7 respectively, the ledge 6 being formed at the back of the front plate of the assembler 8, and the ledge 7 being formed at the front of the back plate of the said assembler. There is a further ledge 9 preferably on the back of the front plate of the assembler 8 and parallel with the ledge 6 and with its upper or supporting surface at a height above that of the ledge 6 equal to the height of the formative cavities 2 above the formative cavities 3 on the matrices themselves. The ledge 9 stops short of the entrance 65 mouth 10 of the assembler 8 by a distance not less than the thickness of the thickest matrix in a font.

So far as has been above described the assembler mechanism is of ordinary construction.

Between the entrance mouth 10 and the adjacent end of the ledge 9, there is a supplementary ledge 11 preferably formed integral with a vertical plate or slide 12 and capable of a vertical motion between two positions, in the lower of which, as shown in Fig. 4 it is in register with, and virtually forms a continuation of, the ledge 9, and in the upper of which, as shown in Fig. 3, it is 80 out of register with the ledge 9 and at a height considerably above it so as to allow the matrix lugs 4 to pass beneath it on to the ledge 6 which latter, as ordinarily, extends to the entrance mouth 10. The supplementary ledge 11 may be guided in its vertical adjustment by means of screws 13 which pass through a slot 14 in the slide 12 and screw into the front of the assembler 8, there being provided spring washers 15 on the 85 screws 13, or other equivalent devices, for presenting sufficient friction for retaining the supplementary ledge 11 in either of its adjusted positions, until the operator positively moves it from such position for effecting a change of font. For facilitating the adjustment of the ledge 11 the slide 12 is provided with a handle 16.

When the supplementary ledge 11 is in its upper position, in which it is shown in Figs. 100 1 and 3, the feet or, more strictly speaking, the lugs 4, 5 of the matrices entering the assembler 8, are received upon, and travel along the ledges 6 and 7, so as to present the normal formative cavities 2 in the composing line. When the ledge 11 is in its lower

position, in which it is shown in Fig. 4, and therefore in register with the ledge 9, the lugs 4, rest upon it, so as to present the variant formative cavities 3 in the composing line, which presentation will be maintained for the matrices already entered, by the ledge 9. This invention allows the operator to change the position of the ledge 11 as soon as he is ready to change font in his composition, so that if, immediately after a matrix has been stopped by the shelf 11 for assembling its variant formative cavity 3 in the composing line, as in Fig. 4, it is required to assemble a matrix with its normal 15 formative cavity 2 in the composing line as shown in Fig. 3, and the shelf 11 is raised for that purpose, as shown in that figure, there is no necessity to manually push the "variant" matrix off the shelf 11, as has heretofore been the practice, because this "variant" matrix will be automatically pushed off the said shelf 11 by the pressure of the following matrices whether assembled 20 "normal" or "variant".

25 The assembler of the Mergenthaler linotype machine is raised quickly after it has received its line, thereby imparting a certain momentum to the matrices in it and one which, unless thwarted, would disturb the 30 alinement of the composed line of formative cavities. This momentum is thwarted in the case of those of the normal font matrices which have passed the supplementary ledge 11, by the fixed ledge 9, under which the lugs 35 4 of the said matrices are then situated, and in the case of the variant font matrices it is thwarted by a rod up to which the assembler 8 in its ascent brings them; this rod constitutes no part of the present invention and is 40 therefore not represented in the accompanying drawings. In the case of those of the normal font matrices which have not passed the supplementary ledge 11, the above-named momentum is thwarted by a horizontally 45 slidable detent 17, Figs. 3 and 5, capable of sliding through the back of the assembler 8 so that the forward end of such detent may be caused to either project to the front of such back and into the assembler as 50 shown in Fig. 5 or not to so project as shown in Fig. 3; in the former of these two last-named positions the forward end of the detent 17 projects over the matrix lugs 5 and thereby holds the matrices down upon the ledges 6, 7, and in the latter of such positions it is out of the path of the matrices entering 55 the assembler. The detent 17 is operatively connected with the lower end of a lever 18 pivoted to the back of the assembler 8 and 60 upon whose upper end acts a spring 19 which constantly tends to move the detent 17 into the matrix-engaging position in which it is shown in Fig. 5. At its back, the upper end of the lever is adapted to engage with a stationary cam 20 fast to the face plate 21 of

the machine, this cam being so situated as to withdraw the detent 17 from within the assembler when the latter has almost completed its descent and to maintain it in such withdrawn position until just after the commencement of the assembler's ascent.

The before described ledge 9 may be either fast to the assembler or movable therein, in any of the ways already known in connection with such devices.

In respects other than those hereinbefore particularized the devices shown in the accompanying drawings may be of ordinary construction.

I claim,

1. In a typographical composing machine in which matrices are assembled in an assembler, and in combination, a plurality of matrix supporting shelves in said assembler, one of said shelves being shorter than said assembler; and a vertically adjustable shelf in said assembler movable into alinement with the short shelf to complement the length thereof.

2. In a typographical composing machine in which matrices are assembled in an assembler, and in combination, lower matrix-supporting shelves in said assembler; an upper matrix supporting shelf in said assembler of shorter length than said assembler; and a vertically adjustable shelf in said assembler movable into alinement with said upper shelf to complement the length thereof.

3. In a typographical composing machine in which matrices are assembled in an assembler, and in combination, a matrix-supporting shelf in said assembler and of shorter length than said assembler; and a vertically adjustable matrix-arresting shelf in said assembler movable into alinement with said shelf to complement the length thereof and into the path of the entering matrices; and movable out of matrix-arresting position.

4. In a typographical composing machine in which matrices are assembled in an assembler, and in combination, lower matrix-supporting shelves in said assembler; an upper matrix-supporting shelf in said assembler of shorter length than said assembler; a vertically adjustable shelf in said assembler movable into alinement with said upper shelf to complement the length thereof; a matrix detent operative in said assembler in that part of said assembler occupied by the complementary shelf; and detent operating means adapted to automatically project said detent into operative position and withdraw it therefrom.

5. In a typographical composing machine in which matrices are assembled in an assembler, and in combination, lower matrix-supporting shelves in said assembler; an upper matrix-supporting shelf in said as-

sembler of shorter length than said assembler; a vertically adjustable shelf in said assembler movable into alignment with said upper shelf to complement the length thereof; a matrix detent operative in said assembler in that part of said assembler occupied by the supplemental shelf; a spring normally projecting said detent into operative position; and cam gear operative at prede-

termined moments to withdraw said detent 10 against the action of said spring.

In witness whereof I have hereunto set my hand in the presence of two witnesses.

FERDINAND JOHN WICH.
